UNITED STATES PATENT OFFICE.

JAMES McCONVILLE, OF MONTREAL, QUEBEC, CANADA.

WRENCH ADJUSTMENT.

Application filed December 7, 1925. Serial No. 73,801.

- The invention relates to a wrench adjustment, as described in the present specification and illustrated in the accompanying drawings that form part of the same.
- 5 The invention consists essentially of the novel features of construction pointed out in the claim for novelty following a description containing an explanation in detail of an acceptable form of the invention.
- 10 The objects of the invention are to increase the efficiency of a wrench and thereby reduce the labor cost; to strengthen the jaws of the wrench and insure a firm grip of the work; to avoid slipping of the jaws and the danger of injury to the hands of the operator; to facilitate the adjustment in a wrench that will make it easy to control; and generally to provide a tool cheap to manufacture, durable in construction, and 20 efficient for its purpose.
- In the drawings, Fig. 1 is a sectional view of the wrench head showing the adjustment, and
- 25 Fig. 2 is an elevational view of the wrench head showing the handle broken away.
- Like numerals of reference indicate corresponding parts in the various figures.
- Referring to the drawings, the wrench 10 is formed in the usual manner having the 30 fixed jaw 11 and movable jaw 12 forming a part of the rack 13 having the teeth 14 which intermesh with the worm 15.
- The worm 15 is fixedly mounted on the spindle 16 and is secured thereto by the pin
17. The end 18 of the spindle terminates 35 in a bearing 19 in the wrench and the end 20 of the spindle projects through the wrench head 21.
- The knurled lock-nut 22 has a spring split washer 23 and is threaded on the threaded 40 end of the spindle 20 and is adapted to be tightened thereon.
- In the operation of this invention the jaws are first suitably spaced for the work and the lock-nut is then tightened and makes 45 the sliding jaw rigid with its fixed jaw.
- Many varying constructions can be made embodying the adjustment means as described without departing from the spirit of the invention.
- 50 What I claim is:—
- A wrench comprising a fixed jaw and a handle, the latter having a worm recess and spindle bearings at either end of said recess, a spindle journaled in said bearings and 55 having a threaded end projecting beyond one side of the handle, a worm fixedly mounted on said spindle within said recess, a movable jaw having a rack coacting with said worm and sliding into said fixed jaw 60 and thereagainst, a knurled lock-nut threaded on the threaded end of said spindle, and a spring washer introduced between said lock-nut and the side of the handle.

Signed at Montreal, Canada, this 27th day 65 of November, 1925.

JAMES McCONVILLE.
